UNITED STATES PATENT OFFICE.

CHARLES LIPPINCOTT AND JAMES PATTERSON, OF PHILADELPHIA, PA.

DESIGN FOR A TUMBLER-HOLDER.

Specification forming part of Design No. 6,544, dated April 1, 1873; application filed March 19, 1873.

To all whom it may concern:

Be it known that we, CHARLES LIPPINCOTT and JAMES PATTERSON, both of the city and county of Philadelphia, State of Pennsylvania, have invented a Design for a Tumbler-Holder, of which the following is a specification:

Our design for a tumbler-holder is clearly illustrated by the perspective view of the accompanying drawing.

The holder has an annular frame, *a*, of open work, to one side of which is secured the handle *b*, the latter being of a character too clearly shown in the drawing to need description. The holder has four feet, *c*, which with medallions *d* are secured to or form part of

the frame. The central figure in each medallion represents a fountain, of which the foot beneath constitutes the basin.

We claim—

The design for a tumbler-holder, substantially as described, and as illustrated in and by the accompanying drawing.

In testimony whereof we have signed our names to this specification in the presence of two subscribing witnesses.

CHAS. LIPPINCOTT.
JAMES PATTERSON.
